UNITED STATES PATENT OFFICE.

THOMAS EDGAR ADAMS, OF CLEVELAND, OHIO, ASSIGNOR TO THE BRUSH ELECTRIC COMPANY.

DOUBLE-POLE TROLLEY.

SPECIFICATION forming part of Letters Patent No. 496,681, dated May 2, 1893.

Application filed June 11, 1889. Serial No. 313,822. (No model.)

To all whom it may concern:

Be it known that I, THOMAS EDGAR ADAMS, of Cleveland, in the county of Cuyahoga and State of Ohio, have invented certain new and useful Improvements in Double-Pole Trolleys and Stands for Electric Street-Railroads; and I do hereby declare the following to be a full, clear, and exact description of the invention, such as will enable others skilled in the art to 5 which it appertains to make and use the same.

My invention relates to an improvement in double pole trolleys and stands for electric street railways, the object being to provide each of the two trolleys of electric railways 15 with a separate flexible supporting pole to insure independent adjustment and support to each trolley.

A further object is to provide a single supporting stand with two independent adjustable trolley poles pivotally mounted thereon so that both trolley poles may be rotated in unison and the positions of the trolleys reversed.

A further object is to provide an improved 25 construction of trolley, of trolley pole, and stand.

With these several objects in view my invention consists in certain novel features of construction and combinations of parts as will 30 hereinafter be described and pointed out in the claims.

In the accompanying drawings Figure 1 is a view in side elevation of my invention. Fig. 2 is a similar view in rear elevation. Fig. 3 is a vertical section taken through the 35 trolley stand. Fig. 4 is a detached view in side elevation of the trolley, and Fig. 5 is a longitudinal section and Fig. 6 is a transverse vertical section of the same.

40 A represents the roof of a street car which latter is provided with any suitable electric motor and apparatus for propelling it by electricity. To the roof is secured a plank or bed piece A', which serves as a support for the trolley stand which latter is constructed as 45 follows:

B is a cast iron plate which may be circular in form and which is perforated for the insertion of screws or bolts for fastening the 50 plate to the plank A'. Plate B may be provided on its upper and lower sides with the

bosses or hubs a a' to form an extended bearing within which is firmly secured the lower end of the pivot b, which may have its upper end reduced in size as shown in the drawings. 55 On the upper surface of the plate B is placed a wooden block C which is provided with a central hole for the reception of the pivot b. Upon the wooden block is supported a brass contact sleeve D, the lower end of which is 60 formed with an outwardly projecting flange d which serves as an annular seat for the cast metal sleeve E, the latter having a bracket E' formed integral therewith. Bracket E' is 65 suitably perforated for the insertion of screws b' by which it is secured to one side of the wooden block F. The cast metal sleeve E is held in snug contact with the brass sleeve D by means of a split ring F' which encircles the wooden block G which latter is firmly secured on the pivot b. Upon the upper and reduced end of the pivot b is supported an inverted cup-shaped casting H which has an 70 extended bearing on the pivot and hence has a good electrical contact therewith, and the 75 contact surfaces are thoroughly protected against the entrance of rain or snow by the closed upper end of the casting H. The casting H is formed integral with a bracket I which is fastened to the wooden block on the 80 side opposite the bracket E'. Brackets E' and H are each provided with a trunnion J upon which is loosely mounted a sleeve K. The outer end of each sleeve is provided with a hole j through which is inserted a pin k 85 which enters one of a series of holes l formed in the outer end of the trunnion. To the periphery of each sleeve is secured the inner end of a spiral spring L, the outer end of which is fastened to the housing M on the lower end 90 of the trolley pole. The housing serves to receive and protect the spiral spring.

N is the trolley pole which may be made wholly of wood, but preferably is made as follows: N' is a tube made of thin steel and is 95 secured at its lower end to the arm N'' of the housing M. Within the upper end of the steel tube is fastened a pole N² made of tough and flexible wood, so that the pole will yield and accommodate itself to any irregularities in 100 the roadway or the conductors.

To the upper end of each trolley pole is

pivoted at n a trolley O . These trolleys are forced in snug electrical contact with the two line wires $P P'$. Each trolley is constructed as follows:— Q is a **U**-shaped metal plate or casting in the form of a shoe the sides of which are arc-shaped. One side of the trolley is constructed with double walls $q q'$ which are separated so as to form an intervening oil chamber q^2 , to which oil is supplied from any suitable oil cup or lubricator R . Oil is fed to chamber q^2 from whence it escapes through the series of feed openings r formed in the inner wall of the trolley and falls upon the renewable contact plate R' which is riveted or otherwise secured on the bottom of the trolley. The wear of the renewable plate R' and of the sides of the trolley, due to their sliding frictional contact with the line wires, is reduced to a minimum by the supply of lubricant to the trolley. S is a spark catcher, and consists of a metal plate pivoted to the trolley and forced upward against the under side of the line wire by means of a spring s . Should the trolley jump out of contact with the line wire, the circuit will still be completed through the spark catcher and the formation of an arc be prevented thereby. S' is a pin removably secured to the trolley and adapted to actuate the line switches. Conductors T and U are connected with the car motor. Conductor T is electrically connected with the brass sleeve D , which is electrically connected with the cast metal sleeve E with which the trolley is electrically connected by means of a suitable conductor. The conductor U is electrically connected with the other trolley through the pivot b , casting H and suitable conductor connecting the casting and trolley. It will thus be observed that each trolley is provided with a separate trolley pole and conductor, and further that while each trolley is permitted to have an independent adjustment, and to be separately detached from the line conductor, both poles and trolleys may be swung around in unison and their positions reversed. The pressure of the trolleys in the line conductors may be readily varied and independently regulated by changing the tension of the spiral springs, it being simply necessary to so adjust the sleeves K to which the spiral springs are secured at one end that any desired pressure may be transmitted to the trolley poles. $V V$ are steel stop pins, secured to the wooden block to limit the forward movement of the trolley poles.

As it is evident that many changes in the form, construction and relative arrangement of parts might be resorted to without departing from the spirit of the invention I would have it understood that I do not restrict myself to the particular construction and arrangement of parts shown and described, but, Having fully described my invention, what I claim as new, and desire to secure by Letters Patent, is—

1. A trolley shoe provided with a chamber

for lubricating material and with an opening for discharging the lubricant onto the face engaged by the line wire, substantially as set forth.

2. A trolley shoe constructed with double side walls arranged to form an intervening oil chamber, substantially as set forth.

3. A trolley shoe constructed with double side walls arranged to form an intervening oil chamber, the inner wall being perforated, substantially as set forth.

4. The combination with a trolley shoe of a lubricator for feeding lubricant to the face of the trolley shoe engaged by the line wire, substantially as set forth.

5. The combination with a trolley shoe, of a spark-catcher plate arranged to press against the under side of the line conductor at one end of the trolley shoe, substantially as set forth.

6. The combination with a stand and a bracket pivotally mounted thereon, of two independent trolleys mounted on said bracket, each trolley having independent devices for holding it in contact with the line wire.

7. The combination with a trolley-pole having a housing secured to its lower end, of a trolley stand provided with a bracket having a journal or trunnion, and a spring inclosed within the housing for forcing the trolley against the line conductor, substantially as set forth.

8. The combination with a housing having a trolley pole secured thereto, and a bracket journal provided with an adjustable sleeve on which the housing is journaled, of a spring one end of which is fastened to the housing and the other to the adjustable sleeve, substantially as set forth.

9. The combination with the bracket journal or trunnion provided with a series of holes, and a sleeve mounted on the bracket journal and provided with a hole and an adjusting pin, of a trolley pole housing journaled on the sleeve, and a spiral spring one end of which is fastened to the housing and the other end to the adjustable sleeve, substantially as set forth.

10. The combination with the trolley stand having a metal sleeve secured thereto, and a conductor connected with the car motor electrically connected with said sleeve of a trolley pole bracket provided with a sleeve or ring that is mounted upon and has a rotary motion on said conducting sleeve, substantially as set forth.

11. The combination with the pivot of the trolley stand and a conductor connected with the car-motor, electrically connected with said pivot, of a trolley bracket provided with a bearing that is supported on said pivot, substantially as set forth.

12. The combination with a trolley stand and two independent trolley poles pivotally mounted thereon of separate electrical connections with each trolley pole, substantially as set forth.

13. The combination with a trolley stand provided with a pivot electrically connected with the motor and with one trolley, of an insulated sleeve on the stand electrically connected with the motor and with another trolley, substantially as set forth.

14. The combination with a trolley pole and shoe, of a removable pin for actuating the line switches, substantially as set forth.

15. The combination with a conductor and a motor car, of a trolley engaging the conductor and a lubricator attached to and carried by the trolley.

16. The combination with an overhead conductor, of a trolley pole carrying at its upper end a contact device for engaging the conductor, and a lubricator.

17. In an electric railway the combination with the collector of a device for supplying a coating to the working conductors attached to and carried by the collector.

18. The combination with a stand and a bracket pivotally mounted thereon, of two independent trolley poles pivotally secured to said bracket each having independent devices for maintaining its trolley in contact with the line wire.

19. In a double suspended system of electric conductors, a duplex contact device comprising separate upwardly spring pressed contact carrying arms movable on both a vertical

and a transverse axis and separate insulated circuit connections between said arms and their stationary supports.

20. In a double suspended system of electric conductors a duplex contact device comprising separate upwardly spring pressed arms, each provided with a current collecting device at its free end and movable on both a vertical and transverse axis, and separate insulated circuit connections between said arms and their stationary support, said connections being also free to move upon a vertical axis without disturbance.

21. In a double suspended conductor system, the combination with a pair of contact arms, a vertical support provided with transverse extensions upon which said arms are movably sustained, tension springs upon the transverse supports, one end of each of said springs engaging one of the arms, the other extremity thereof, being provided with locking mechanism, and locking devices upon the support for securing and retaining the inner ends of the springs.

In testimony whereof I have signed this specification in the presence of two subscribing witnesses.

THOMAS EDGAR ADAMS.
